Dec. 1555

Oliver J. Key, of Lowell, Mass.
Assignor to
The Lowell Manufacturing Co. of same place.
Letter Patent No. 1555, dated March 18, 1862.

The schedule referred to in these Letters Patent and making part of the same.

To all whom it may concern:

Be it known that I, Oliver J. Key, of Lowell, in the County of Middlesex, and State of Massachusetts, have invented and designed a new Pattern for Carpets or other fabrics, of which the following is a full, clear and exact description, reference being had to the accompanying drawings, making part of the same.

Fig. A. is one half of a plain figure surrounded by scrolls, and resting on a ground of heavy mottled work.

In corners 1 and 2. are fourths of figures similar to that of which fig. A. is one half, these figures rest on a ground of light mottled work. Running diagonally from the lower corners to the top of the drawing are the plain bars 3, 4, which separate the grounds before mentioned.

Square blocks 5, 6, rest on these bars, half way between fig. A. and the corners figs. 1 and 2.

Fig. 6. is one half, and figs. 7 and 8. are fourths of large diamonds overlapping the extremities of the bars 3, 4.

The colors employed for the different portions of the design may be varied to suit the taste & wish of the manufacturer.

Claim.

What I claim as my invention and desire to secure by Letters Patent, is the design or pattern for Carpets or other fabrics, herein set forth.
